UNITED STATES PATENT OFFICE.

BENJAMIN R. JOLLY, OF RALEIGH, NORTH CAROLINA.

BUCKLE AND STRAP.

1,333,421.

Specification of Letters Patent.

Patented Mar. 9, 1920.

Application filed November 5, 1918. Serial No. 261,273.

To all whom it may concern:

Be it known that I, BENJAMIN R. JOLLY, a citizen of the United States, and a resident of Raleigh, in the county of Wake and State 5 of North Carolina, have invented a new and Improved Buckle and Strap, of which the following is a full, clear, and exact description.

This invention relates to buckles and also 10 to the combination of a buckle and strap and has for an object the provision of an improved construction of buckle whereby a very thin structure may be used, while at the same time acting as an efficient connecting means.

Another object in view is to provide a buckle arranged with a tongue positioned to automatically engage openings in the strap for preventing accidental disengagement 20 thereof and also for holding the strap normally in a given position.

A further object of the invention is the provision of a buckle formed with a pressed out portion which may be in the nature of 25 an eyelet integral with the buckle or retaining spurs integral with part of the buckle.

An additional object is the provision of a buckle arranged with a central section which may be pressed out for forming retaining 30 eyelet members or may be cut out for receiving a separate eyelet or rivet for holding the buckle in position on a strap or other article.

In the accompanying drawing:

Figure 1 is a top plan view of a buckle 35 and strap disclosing an embodiment of the invention.

Fig. 2 is a longitudinal vertical section through Fig. 1 on line 2—2.

Fig. 3 is an enlarged fragmentary sectional view showing the buckle in a closed or locked position.

Fig. 4 is a top plan view of a slightly modified form of buckle to that shown in Fig. 1.

Fig. 5 is a sectional view through Fig. 4 on line 5—5.

Referring to the accompanying drawing by numerals, 1 indicates a covering strap used in connection with wrist watches. 2. 50 This strap is held in place by a clamping strap 3 having apertures 4 at one end and a buckle 5 at the opposite end. The detail construction of the strap 1 and the use to which it is put forms no part of the present 55 invention. The strap 3, however, is connected with the buckle 5 in such a manner

that the end 6 will project preferably a short distance beyond the buckle as shown in Figs. 1 and 2 so that when end 7 of strap 3 is brought around and forced beneath the front 60 end or front bar 8 of buckle 5 the end 6 will be in position for guiding the end 7 correctly into buckle 5. When the end 7 has been forced the desired distance through buckle 5 the same may be guided so that the 65 tongue 9 of buckle 5 will project through one of the apertures 4 whereupon the parts are in a proper locked position as shown in Fig. 3. In case the end 7 should be pressed accidentally, or the strap should become loose 70 and move from the opposite direction off the tongue 9 it will again move on to said tongue when the strap is pulled as the tongue 9 is preferably slightly resilient and normally rests at its outer end against the end 6 of 75 strap 3. The front bar 8 merges into side bars 10 and 11 which in turn merge into a central section 12, said central section being sufficiently wide to allow an ample quantity of material thereof to be pressed into the eyelet member 13 which is forced through the strap 3 and is clenched over in the usual manner of eyelets so as to not only fasten the buckle 5 firmly to the strap, but also prevent the accidental rotation of the buckle. The 80 central bar 12 merges into side bars 14 and 15 which in turn merge into the rear bar or keeper 16. All the side bars are bent slightly upwardly or away from the body 12 as shown particularly in Fig. 2 so that when 85 the end 7 of strap 3 is forced through the buckle it will extend substantially in a straight line through the buckle (Fig. 3). This form of buckle is such that it may be made either from thin material where it is 90 subject to light work, as for instance on a wrist watch, or if desired made from much heavier material, as for instance an ordinary belt for the waist. The body 12 extends somewhat into the space between the side 95 bars 14 and 15 in order to provide ample material for producing the eyelet 13 and also for causing the eyelet 13 to be of an appreciable size.

In Figs. 4 and 5, however, instead of using 100 the part of the material of body 12 an aperture is made in said body and a separate eyelet 17 is placed in position for clamping the buckle in place.

The structure shown in Fig. 2 will positively 110 prevent any rotation of the buckle and the retaining means are simple and ef-

fective as they are part of the body of the buckle. The buckle has been shown on a strap 3 used with a wrist watch, and a strap indicated as 1 in Fig. 1, but it will be evident that the buckle could not only be used for this purpose and in this manner, but for a wide variety of purposes in any way without departing from the spirit of the invention.

What I claim is:

10 A buckle comprising a longitudinally enlarged and widened central body portion,

two end portions extending therefrom to form a frame, one of said end portions having an inwardly extending integral tongue and a clencher fastener on said central body portion securing one end of a strap flat against the same in a rectilinear position, whereby looping or bending of the strap is obviated and a flat securing means is provided, with a single thickness of strap.

BENJAMIN R. JOLLY.
